W. M. COOPER

AUTOMATIC DOOR

Filed Dec. 19, 1922

ATTORNEY.

UNITED STATES PATENT OFFICE.

WILLIS M. COOPER, OF NORMAN, OKLAHOMA.

AUTOMATIC DOOR.

Application filed December 19, 1922. Serial No. 607,879.

To all whom it may concern:

Be it known that I, WILLIS M. COOPER, a citizen of the United States, residing at 411 Elm Ave., Norman, in the county of Cleveland and State of Oklahoma, have invented a certain new and useful Invention in Automatic Doors, of which the following is a specification, reference being had to the accompanying drawings.

19 This invention relates to an automatically operable opening-closure, in particular, and primarily a door for barns, garages, warehouses and similar places where the weight of a vehicle can be used for the purpose of
 20 operating the same. There are various objects of the invention that will appear from a reading of the following specification, and, among the important of which, are those which provide for the opening of the door from pressure, and closing the same by gravity, and depending either on a supplemental lock or the weight of the door for locking the same against entry. An additional object of the invention is to store the opening
 25 closure when not in use, out of the way of traffic, and to provide compensating instrumentalities for the operative mechanism, when temperature and climatic conditions change the size or weight of the closure.
 30 As previously stated, other objects of the invention will appear from a further and more complete reading of the following specification and claim.

On the sheet of drawings, accompanying
 35 and forming a part of this specification,

Figure 1 shows the device in closed arrangement, and with side-entry door,

Figure 2 is a plan view of a detail construction, and

40 Figure 3 is an isometric view of the structure, and partly broken away to indicate detail.

In these several views, similar characters of reference indicate similar parts.

45 In runways 4 and 5, respectively, forming the jambs for an opening 6, a sectional door 7 is adapted to reciprocate to open and close, at will, at the instance of automatic mechanism, controlled by weight. This sectional door, of whatever construction and material, is adapted to be stored or rolled up on a pair of studs 8, after passing over an additional pair of secondary studs 9 that assist in guiding the door in proper alignment with the guides 4 and 5.

To the out side or edge of the studs 8 is secured a suitable fastening element 10, flexible in its nature and to which the elements of the sectional door are affixed, to allow ease of rolling or storing. A bearing 60 suitably constructed, and likewise suitably affixed, in a manner not shown, to the structural work of the building, and at the upper part thereof, contains the spindles 12 for the studs 8 and the spindles 13, for the 65 rollers 9. The construction of this arrangement, of course, will be of any suitable type best calculated to meet general manufacturing or constructional requirements.

Upon a shaft 14 suitably journaled in 70 said bearing is a gear 15, that meshes with a pinion 16 that is associated with the spindles 12 of the studs 8. A sheave 17 is then provided on the one spindle 12 and this may be provided with a counter-balance 18 75 for compensating for inequalities and varied weights in the door 7.

On one end of the spindle 14, the same one carrying the gear 15 is a pinion 19 which is designed to be in mesh with a 80 rack-bar 20, guided in place, in any suitable manner, as for instance by a roller bearing 21, and this rack bar, one on each side of the door or door operating construction, is 85 suitably associated with a link 22 that goes to the bottom of the opening 6 and there connects with a bar 23 passing through openings 24 in the jamb and reaching across said opening connecting two of such bars or links 22, so that the mechanism and its operation 90 may be in duplicate on each side of the door.

This bar is sufficiently elevated from the "plate" or "sill" of the building to permit of raising and lowering, and to it, in a suitable and an efficient manner are applied 95 run-ways 25, 26, 27 and 28, two extending to the outside, and two to the inside of the building.

We will now consider that the door 7 is closed and "spent" from off the spindles 8. 100 The weight of said door is sufficient, ordinarily, to keep it in closed position. A vehicle commencing to climb these runways, in either direction will exert enough pressure on the bar 23 to cause a downward pull on the rack-bars 20, and this power-motion will be transmitted to the pinions 19 and gears 15 and to the pinions 16. This will cause the studs 8 to rotate, and the door-elements binder 10 being fastened to these 110

studs 8, will cause the door to wind up on these studs and lift itself automatically out of the opening 6 for free entry therethrough, and as the vehicle recedes from off the runways at the inside of the building, the door will automatically close of its own weight. When the vehicle desires exit, the operation will be repeated in the reverse order, and the door may automatically close after the vehicle has departed.

As to details of construction, herein expressed it will be understood that they may be changed in any mechanical and efficient way to suit constructional necessity without departing from the spirit of this invention, and as to the nature or construction of the door the same may be varied at will.

It will now be seen that there is provided an efficient and effective door for the purposes desired and which can be automatically

lifted and lowered by a vehicle intending to pass through said door.

Having thus described this invention, I claim:

An automatically operable raising and lowering door for automobile garages consisting of a sectioned door, a roll upon which the door is rolled up and stored and unwound therefrom, gear mechanism for controlling the movement of the roll, a rack meshing with the gear mechanism, running boards controlling the movement of the rack, all so that when pressure is put on the running boards the door will raise.

Signed at Oklahoma City, in the county of Oklahoma and State of Oklahoma, this 29th day of November, in the year of our Lord, nineteen hundred and twenty-two.

WILLIS M. COOPER.
